R. W. DAVENPORT

REFRIGERATING APPARATUS

Original Filed April 11, 1924

Ranson W. Davenport
INVENTOR

UNITED STATES PATENT OFFICE.

RANSOM W. DAVENPORT, OF DETROIT, MICHIGAN.

REFRIGERATING APPARATUS.

Application filed April 11, 1924, Serial No. 705,809. Renewed September 16, 1925.

To all whom it may concern:

Be it known that I, RANSOM W. DAVENPORT, a citizen of the United States, residing at Detroit, in the county of Wayne and the 5 State of Michigan, have invented new and useful Improvements in Refrigerating Apparatus, of which the following is a specification.

This invention is an improvement in refrigerating apparatus and has among its objects the provision of machines and apparatus particularly adapted to employ as part of the working substance, hydrocarbons, sulphur di-oxide, or other agents which tend to 10 combine with or dissolve ordinary lubricants and injure or destroy their lubricating value.

All refrigerating systems must employ a pump. The form most generally used is the 20 reciprocating or piston compressor, and it is considered essential that some lubricant be supplied to its working parts. It is the common practice to so construct and arrange the compressor that the crank case is fully enclosed and is under the same pressure as the evaporator, i. e., the low-side pressure. The oil in the crank case is therefore under that 25 pressure also, and its vapor mingles with that of the refrigerant. It is of course impossible with such constructions and arrangements, to permit any liquid refrigerant to be present in the crank case even if it were desired to use it as the lubricant, since the 30 compressor itself would then become the refrigerator.

On the contrary, it is impossible with the 35 commonly known constructions and arrangements, to put the crank case under high-side or condenser pressure with a view to using the refrigerant itself as the lubricant, without suffering a great loss in power since the suction stroke would then have to be made against the high pressure; and the power required would be practically all lost. Nor 40 would it wholly overcome this disadvantage to use a common two-cylinder construction, for while theoretically the pressures on the backs of both pistons are equal, in fact the loss is still prohibitive due to the excess bearing loads and also to the unavoidable difference in the velocities of the separate pistons at different points in their travel. For these 45 reasons, it has always been considered impossible to use the refrigerant as the sole lubricant, although the very serious disad-

vantages in the use of oils are commonly known.

One of the principal objects of this present invention is to provide a reciprocating pump or piston compressor which is peculiarly and distinctively adapted to permit condenser or high-side pressures to be carried in the crank case with no increase whatever in the power required to operate the pump, thus for the first time making it possible to use the refrigerating liquid itself as the lubricant, and eliminating one of the most serious problems in the refrigerating art.

Another object of my invention is to provide a pump or compressor of large volumetric displacement yet of moderate size for use in such circumstances as require a compact machine. For example, in refrigerating systems employing refrigerants of low vapor 70 tensions like water or alcohol, the volume of vapor which must be pumped is so considerable that, heretofore the reciprocating pump has been considered impracticable on account of its size and weight.

Other objects of my invention will appear hereafter.

The accompanying drawing is a view, partly in section, of a preferred form of my invention, showing its operative relation to 85 the condenser, expander etc.

In the accompanying drawing, 1 is a prime mover geared to the crank-shaft 2 of the compressor or pump. The piston 3, having packing rings 4-4 and 5-5 at both ends, is 90 reciprocated by the shaft 2 through the linkage or connecting rod 6, bearing in the piston at 7 between the packings 4 and 5. The cylinder of the pump is adapted to form a housing 8 for the shaft and linkage. At 9 is 95 shown a condenser connected in the usual manner to the expander 11 through the expansion valve 10, the whole comprising the well known compressor-condenser-expander circuit.

The pipe 12 and reservoir 13 connect the condenser with the housing or crank case 8 of the compressor, and may be arranged to feed liquid from the condenser into the pump in any well known manner.

My invention operates substantially as follows: Upon starting the motor 1, the piston is reciprocated by shaft 2, linkage 6 and bearing 7, and pressure is developed in condenser 9 which is transmitted through 105

12 and 13 back into the crank case 8. But since the piston 3 simply moves as a whole and nothing moves in or out of the crank case, there is absolutely no change of volume 5 therein, and consequently neither the pressure nor the bearing load is altered in the least. The condensate formed in 9 is now fed back, a proper amount at a time, through the pipe 12, and finds its way to the various 10 rubbing surfaces. The amount may be regulated in any suitable manner well known to the art, as by a needle valve or other sight feed device.

It will be clear that I have provided a 15 system whereby oils may be eliminated from the apparatus entirely. It is also obvious that the apparatus may be very compact, thus enabling me to use refrigerants of low vapor tension, if desired.

20 I do not desire to claim as my invention any specific means for operating a pump piston; nor do I claim any specific means for lubricating a compressor; for by the aid of the principles set forth above, anyone 25 skilled in the art may easily embody my invention in a variety of equivalent forms.

I claim:

1. In a refrigerating system having a compressor, a condenser, and an evaporator, 30 means for conducting fluids from said condenser into the crank case of said compressor to lubricate the parts thereof.

2. In a refrigerating system having a compressor, a condenser, and an evaporator, a 35 pipe connecting said condenser to the crank case of said compressor whereby fluid from the condenser is utilized for the lubrication of the compressor.

3. In a refrigerating system having a compressor, a condenser, and an evaporator, 40 means for collecting at least a portion of the condensate of said condenser, and means for conducting said condensate into the crank case of said compressor.

45 4. Apparatus forming a closed cycle system for producing refrigeration comprising

a compressor, a condenser, an evaporator, said parts being suitably connected together, a reservoir connected to the lower portion of said condenser for receiving a part of 50 the condensate thereof, and means including a pipe extending from said reservoir to the crank case of said compressor for conducting condensate in limited amount thereto to act as a lubricant for the working parts of 55 said compressor.

5. A refrigerating compressor having a piston chamber, a piston therein, a crank-case inclosing movable parts for operating the compressor, and a fluid connection 60 between said crankcase and the discharge line of said compressor.

6. A refrigerating compressor having a piston chamber, a piston reciprocable therein, a crankcase inclosing movable parts for 65 actuating said piston, and a pipe connecting said crank case with the discharge port of said compressor.

7. Combined in a refrigerating compressor having a reciprocating piston and 70 a crankcase, a piston packing adjacent each end of said piston; a bearing in said piston located between said piston packings; a crankshaft supported within said crankcase transversely of said piston; linkage within 75 said crankcase connecting said crankshaft and said bearing; and a pipe connecting said crankcase with the discharge port of said compressor.

8. In a compressor - condenser - expander 80 type of refrigerating apparatus including a compressor having a reciprocating piston and a crankcase; packings adjacent the ends of said piston; means connected to said piston between said packings adapted to reciprocate 85 the piston; said reciprocating means being suitably disposed within said crankcase; and means for feeding liquid from the aforementioned condenser into said crankcase.

RANSOM W. DAVENPORT.
